UNITED STATES PATENT OFFICE

BERNICE SQUIER AND BLANCHE SQUIER, OF BATTLE CREEK, MICHIGAN

TOY

Application filed February 4, 1929. Serial No. 337,223.

The main object of this invention is to provide a wheeled toy of the stuffed flexible type which is well adapted for very small children and one with which children are not likely 5 to injure themselves.

Objects pertaining to details and economies of our invention will definitely appear from the description to follow. The invention is pointed out in the claims.

10 A toy which embodies the features of our invention is clearly illustrated in the accompanying drawing, in which:

Fig. 1 is a perspective view of an embodiment of our invention.

15 Fig. 2 is a fragmentary section on line 2—2 of Fig. 1.

Fig. 3 is a fragmentary section on line 3—3 of Fig. 2.

In the embodiment illustrated in the accompanying drawing, the body element designated generally by the numeral 1 includes integral leg parts 2 and 3. This body element is formed of a flexible or fabric casing 4 and a filling 6, the filling being of sufficient 25 density so that the body element retains its shape and at the same time is flexible and the legs and body being bendable.

Within the casing in the lower ends of the leg parts I enclose spherical bearing members 30 7 for the spindles 8. These bearing members fit within the lower ends of the leg parts and are held in position therein by the filling material 6, see Figs. 2 and 3. The bearing members have holes 9 therein while the casing has alined holes 10 through which the spindles are arranged. Spherical rollers 11 are secured on the ends of the spindles.

Our wheeled toys are very attractive to children and may be handled by small children without liability of breaking the toys or injury to the child.

We have not illustrated various embodiments which we contemplate as we believe this disclosure will enable those skilled in the art to embody or adapt our improvements as may be desired.

Having thus described our invention what we claim as new and desire to secure by Letters Patent is:

50 1. In a toy, the combination of a body ele-

ment including integral leg parts, said body element comprising a casing of flexible material and a filling therefor, spherical bearing members arranged at the lower ends of said leg parts and enclosed within said casing and partially embedded in said filling material, said casing and bearing members having alined holes therein, spindles arranged through said alined holes, and spherical rollers on the ends of said spindles.

2. In a toy, the combination of a body element including integral leg parts, said body element comprising a casing of flexible material and a filling of fibrous material, bearing blocks arranged at the lower end of said leg parts and enclosed within said casing and partially embedded in said filling material, said casing and bearing members having alined holes therein, spindles arranged through said alined holes, and rollers on the 70 ends of said spindles.

In witness whereof we have hereunto set our hands.

BERNICE SQUIER. 75
BLANCHE SQUIER.
